UNITED STATES PATENT OFFICE.

FREDERICK KAMPFE, RICHARD KAMPFE, AND OTTO KAMPFE, OF
BROOKLYN, NEW YORK.

DESIGN FOR A RAZOR-STROP.

SPECIFICATION forming part of Design No. 23,576, dated August 21, 1894.

Application filed June 21, 1894. Serial No. 515,311. Term of patent 7 years.

To all whom it may concern:

Be it known that we, FREDERICK KAMPFE, RICHARD KAMPFE, and OTTO KAMPFE, citizens of the United States, and residents of Brooklyn, in the county of Kings and State of New York, have invented a new and original Design for Razor-Strops, of which the following is a specification.

In the accompanying drawing, forming a part of this specification a face view of a razor strop of our new and original design is shown.

The leading features of our new design for razor-strops are: a razor strop having at each end an end piece bearing on its face, a central star and an aperture of circular shape at each side of the star and scroll and leaf ornamentation around the star and circular apertures, a handle at one end piece which handle has an eye at its free end, an open cross piece adjacent to the eye or loop and a V-shaped part between the cross piece and the end piece, and finally a V-shaped hanger with an eye or loop at its free end at the other end piece.

In the drawing A, is the strop, B and C the end pieces. D the handle, E the eye or loop at the end of the same, F, the cross piece, and G the V-shaped part.

H is the V-shaped hanger and J the eye or loop at the free end of the same.

Having described our invention, what we claim as new, and desire to secure by Letters Patent, is—

The design for a razor strop substantially as herein shown and described.

In testimony that we claim the foregoing as our invention we have signed our names, in presence of two witnesses, this 13th day of June, 1894.

FREDERICK KAMPFE.
RICHARD KAMPFE.
OTTO KAMPFE.
